ALBERT R. THOMPSON, OF SAN JOSE, CALIFORNIA, ASSIGNOR TO ANDERSON-BARNGROVER MFG. CO., OF SAN JOSE, CALIFORNIA, A CORPORATION OF CALIFORNIA.

PACKAGE-HANDLING VALVE FOR STEAM-TIGHT CHAMBERS.

1,188,581.

Specification of Letters Patent. Patented June 27, 1916.

Application filed April 16, 1915. Serial No. 21,937.

To all whom it may concern:

Be it known that I, ALBERT R. THOMPSON, a citizen of the United States, residing at San Jose, in the county of Santa Clara and State of California, have invented certain new and useful Improvements in Package-Handling Valves for Steam-Tight Chambers, of which the following is a specification.

10 My invention relates to the class of controlling devices or valves commonly used in connection with the entrances and exits of chambers or compartments to and from which packages are admitted and discharged, the function of said valves being to admit and discharge the packages without permitting the escape or loss of the steam or other fluid to which the goods are subjected within said chamber. The most 15 common application of these devices or valves is to chambers containing steam, such, for example, as cookers used in the canning art, and they are especially desirable and necessary in machines of this type in which 20 the cooking is due to steam under pressure.

It is the object of my invention to provide a simple, effective and economical package-handling valve for steamtight chambers; and to this end my invention consists 25 in the novel device for this purpose which I shall now fully describe by reference to the accompanying drawings, in which—

Figure 1 is a plan view of my package-handling valve. Fig. 2 is a section on the 30 line $x-x$ of Fig. 1. Fig. 3 is an end view of the device. Figs. 4, 5, 6 and 7 are dia-grammatic views showing the several positions of the opposing pistons.

For convenience I shall herein describe 40 my invention in terms of what is known in the canning art as cookers, and the packages to be handled as cans, though it is to be understood that my device is applicable to any chamber, the processing medium in 45 which is any fluid, and the material received and discharged is any form of package.

1 is the box or casing of the cooker and 2 is a connection to supply it with steam. The package opening 3 of the box, from its 50 position here shown, is a can inlet, though in another position and arrangement it could be the can outlet. For illustration, however, I shall describe it as the can-inlet.

4 is a cylinder, from the side of which

extends a tight runway 5, the foot 6 of which is secured to the cooker box 1, in such position that the lower end of said runway communicates with the box through the can-inlet 3. The upper end of the runway communicates with the cylinder 4 through a port 7 in the side of the cylinder. Extending from the other side of the cylinder is a chute 8, the lower end of which communicates with said cylinder through a port 9, which is out of line with the port 7 being 65 to one side thereof, as is shown. Bolted to end lugs 10 on the side of the cylinder nearest the box are the brackets 11, one at each end. Each of these brackets carries a pair of guide rolls 12, one above and one below. 70 Within the cylinder are the steam tight pistons 13 and 14. The piston 13, the one at the left, has a bar 13' which is guided between one pair of guide rolls 12, and the piston 14, on the right, has a bar 14' which is guided 75 between the other pair of rolls 12. Secured to end lugs 15 on the side of the cylinder are brackets 16 which carry the cam shaft 17. Upon the cam shaft, at the left, is carried a cam 18; and another cam 19 is carried by 80 said shaft at the right. A stud 20 on the piston-bar 13' plays in the cam 18, and a stud 21 on the piston bar 14' plays in the cam 19. These cams have shapes which can best be expressed in terms of function and 85 effect, as will now be understood by a description of the operation of the device, given in connection with Figs. 4 to 7.

The rotation of the cam shaft 17 in the direction indicated by the arrow in Fig. 1, 90 will cause the cams to move the pistons back and forth. When the pistons are in the position indicated in Fig. 4, they are separated by a space about equal to and in line with the port 9 in the cylinder, and the piston 13 95 covers the cylinder port 7, so that no steam can escape from the box 1, through the closed runway 5. A can, now rolled down the chute 8, will enter the cylinder 4, through the port 9, and will lie between the two pistons. Both pistons now move over to the left, carrying the can between them, until said can is aligned with the cylinder port 7, with the pistons lying on each side of said port, as is shown in Fig. 5. In this position 105 the piston 14 covers the port 9. The can then rolls through the port 7, into and through the closed runway 5, and through

the inlet 3 into the box 1. Now, while the piston 14 remains at rest in the position last mentioned, for a brief moment, the piston 13 moves forward toward the piston 14, thereby forcing the steam back from between the two pistons into the runway until, as shown in Fig. 6, the faces of the two pistons about meet, and the port 7 is closed. Then both pistons move together to the right, until the piston 13 reaches the near line of the port 9 where it stops, while the piston 14 continues to move to the right to the far line of the port 9, thus reaching the position shown in Fig. 7, which is a repetition of that shown in Fig. 4; and a second can will now be received in the space between the two pistons; whereupon the operation is repeated. Thus the cans are fed to the cooker without the loss of any steam, a result which, though important, has heretofore been difficult of accomplishment, especially where, as is now deemed good practice, the steam in the box is under pressure.

I claim:—

1. A package-handling valve for steam-tight chambers, comprising a cylinder having a package inlet port and having also a package outlet port out of line with the inlet port, said package outlet port having a tight communication with the steam-tight chamber; a pair of opposing steam tight pistons mounted within the cylinder, and having a range of movement adapting them, one to control one of said cylinder ports, and the other to control the other cylinder port; and means for operating said pistons to move them in unison from a position in which their adjacent faces are separated in package-receiving relation with the inlet port and in which one of said pistons closes the outlet port, through a range which effects the closing of the inlet port by the second piston prior to the opening of the outlet port by the first piston, to a position in package-delivery relation with said outlet port to then approach their adjacent faces in order to close the space between them and thereby force the steam from said space back through the outlet port and to close said port prior to the opening of the inlet port, and finally to return them to their first position in separated package-receiving relation with the inlet port.

2. A package-handling valve for steam-tight chambers, comprising a cylinder having a package inlet port and having also a package outlet port out of line with the inlet port, said package outlet port having a tight communication with the steam-tight chamber; a pair of opposing pistons mounted within the cylinder, and having a range of movement adapting them, one to control one of said cylinder ports, and the other to control the other cylinder port; and means comprising a pair of cams and connections

for operating said pistons to separate them in alinement with the inlet port in order to receive a package between them, to carry the package between them into alinement with the outlet port and deliver it thereto, to then approach their adjacent faces in order to close the space between them and thereby force the steam from said space back through the outlet port, and finally to return to their first position in alinement with the inlet port.

3. A package-handling valve for steam-tight chambers, comprising a cylinder having a package inlet port and having also a package outlet port out of line with the inlet port, said package outlet port having a tight communication with the steam-tight chamber; a pair of opposing pistons mounted within the cylinder, and having a range of movement adapting them, one to control one of said cylinder ports, and the other to control the other cylinder port; and means comprising a piston-bar carried by each piston, a rotating shaft, a pair of cams carried by the shaft and a stud on each piston-bar coacting with its respective cam for operating said pistons to separate them in alinement with the inlet port in order to receive a package between them, to carry the package between them into alinement with the outlet port and deliver it thereto, to then approach their adjacent faces in order to close the space between them and thereby force the steam from said space back through the outlet port, and finally to return to their first position in alinement with the inlet port.

4. A package handling valve for steam tight chambers comprising a cylinder having a package inlet port and having also a package outlet port out of line with inlet port, said package outlet port having a tight communication with the steam tight chamber, a pair of opposing steam tight pistons mounted within the cylinder and having a range of movement adapting them to receive a package at the inlet port between their adjacent faces and carry it into alinement with the outlet port and deliver it thereto, to then approach their adjacent faces in order to close the space between them, and thereby force the steam from said space back through the outlet port and finally to return to their first position in alinement with the inlet port, said pistons in all positions closing communication between the cylinder ports irrespective of the package.

5. A package handling valve for steam tight chambers comprising a cylinder having a package inlet port and also a package outlet port, out of line with the inlet port, said outlet port having a tight communication with the steam tight chamber, a pair of steam tight pistons mounted in said cyl-

- inder, and adapted to control its ports; and means for operating said pistons both in unison and with relation to each other, to receive a package from the inlet port between 5 their adjacent faces, to carry and deliver it to the outlet port, to displace the steam from between them, and then return them to their normal position, said pistons in all positions closing communication between the cylinder ports irrespective of the package.
6. A package handling valve for steam tight chambers comprising a cylinder having a package inlet port and also a package outlet port out of line with the inlet port, 10 said outlet port having a tight communication with the steam tight chamber, a pair of opposing steam tight pistons mounted in said cylinder and adapted to control its ports, and automatic means for actuating said pistons both in unison and with relation to each other to receive packages from the inlet port between their adjacent faces, to carry and deliver said package to the outlet port, to then approach their adjacent faces to displace the steam from between them, 15 and finally to return them to their first position with relation to the inlet port, and so forth in a continuous cycle of operation said pistons in all positions closing communication between the cylinder ports irrespective of the package.
7. In testimony whereof I have signed my name to this specification in the presence of two subscribing witnesses.
